UNITED STATES PATENT OFFICE.

FRANK HEDLEY, OF YONKERS, AND JAMES S. DOYLE, OF MOUNT VERNON, NEW YORK.

EMERGENCY DOOR-OPERATING APPARATUS.

Application filed August 15, 1923. Serial No. 657,568.

This invention relates to door operating apparatus, and particularly to apparatus for controlling the operation of the doors in subway, elevated and other cars in case of emergency.

The object of the invention is to provide manually operated devices to control the opening operation of motor operated doors such as are employed in subway, elevated, and other railway cars, in case of accident or other emergency which destroys or puts out of commission the devices for normally controlling the door operating motor.

15 A further object is to provide an emergency door operating apparatus of the nature and for the purpose referred to, which is simple in structure and efficient in operation, and wherein the desired control is effected by devices which are easily accessible either inside or outside the car.

Other objects of the invention will appear more fully hereinafter.

The invention consists substantially in the construction, combination, location and relative arrangement of parts, all as will be more fully hereinafter set forth, as shown in the accompanying drawings, and finally pointed out in the appended claims.

30 In the drawing,

Fig. 1 is a view somewhat diagrammatic, parts in elevation, showing a door and motor and operating connections therebetween;

35 Fig. 1^A is a view in transverse section of the construction shown in Fig. 1;

Fig. 2 is a view in elevation, parts in vertical transverse section showing an apparatus for controlling the operations of a car door in case of emergency and constructed 40 in accordance with the principles of our invention.

Fig. 3 is a view in side elevation of the emergency apparatus taken from a point inside the car.

45 Fig. 4 is a view in side elevation showing a portion of the upper part of the emergency door control apparatus taken from the outside of the car.

Fig. 5 is a view similar to Fig. 2 on a somewhat larger scale, showing the upper part of the emergency door controlling apparatus.

50 Fig. 6 is a view in side elevation taken from the inside of the car, of that part of the construction shown in Fig. 5.

Fig. 7 is a view in elevation showing the

lower part of the emergency door operating and controlling apparatus, not shown in Figs. 4 and 5.

Fig. 8 is a view in diagram showing a circuit arrangement employed in connection with our invention.

The same part is designated by the same reference numeral wherever it occurs throughout the several views.

It is a common practice to employ motors to open and close the sliding and other doors used in subway, elevated and other passenger carrying cars, and to control the door operating motor electrically through magnets or magnet valves where the motors are operated by a pressure medium, the control of the motor either for opening or for closing operation, being effected from a convenient point, by a conductor or other employee in charge of the car. Where pneumatic motors are employed, it is customary to provide a magnet valve to effect the control of the motor for the opening movement of the door, and another magnet valve for effecting 80 the control of the motor to close the door. In practice the door operating motor is connected to the door by means of an operating arm or lever in such manner that as the motor is operated in one direction or the other, 85 the door is shifted from one position to another, that is from closed to open position, or from open to closed position, as the case may be.

It is also a common practice in door operating systems of the nature referred to, to provide the door retaining device, or lock arranged to engage the door and hold it in its closed position so as to prevent accidental opening thereof.

90 In such door operating systems and installations, of the nature above referred to, it is the common practice, in order to conserve space, to mount the door operating motor in the space beneath a car seat where, 100 not only is the motor concealed from view, but the door operating arm and the motor control valves as well, are also concealed by being located in the space beneath the car seat.

105 It is among the special purposes of our present invention, to provide an arrangement which will enable any passenger inside the car, or anyone outside the car, to effect the opening of the car door for emergency operation in case of an accident occurring, which would derange or put out of commis-

sion, the electric circuits employed to control the door operating motor in normal operation, or in case of such accident, putting out of commission the supply of power medium to the motor for operating the same, and in carrying out our invention we propose to provide means which are simple and efficient, and which, in case of any such emergency, a passenger or other person without know- 10 ledge of the place of location of the motor or of its control magnets, may be enabled to effect the opening of the car door to permit the release of the passengers or others who might become trapped inside the car by 15 the accident, which necessitates the emergency operation of the door.

Such an emergency door operating apparatus is especially desirable on cars on which, according to modern practice, a conductor 20 or other attendant is not stationed. For example, in the operation of the subway system in various cities, it is now a common practice to place under the control of a single conductor or attendant, at a control station, 25 the control of the operation of the doors of several cars of the train. This leaves one or more cars without a conductor or other attendant, and in case of serious accident resulting from collisions or otherwise, the danger is incurred of the passengers becoming 30 trapped within the car, and either through lack of knowledge as to the location of the door operating members, or of their control valves or method of control or operation, of 35 becoming panic stricken. And, in case such an accident should result in destroying the electrical control of the door operating motors or cutting off the supply of operating medium for such motors, then the occupants 40 of the car would be without means to effect an opening of the car door to release the trapped passengers. It is, therefore, within the special purposes of our present invention, and in order to avert the possibility of 45 panic conditions, and to conserve the safety of the street car travelling public, to provide emergency means to enable the passengers to be released easily and quickly.

Referring to the drawing, reference numeral 10 designates a door. This may be the usual sliding door, such as is employed in subway, elevated or other passenger carrying cars. 11 is the motor, which according to common practice is located beneath a seat 12 inside the car, see Fig. 1^A. A magnet valve indicated at 14, serves to control the opening movement of the motor, and a similar valve 13 serves to control the door closing movements of the motor. An 55 arm 15 actuated by the motor, is connected to the door, whereby the door is actuated to opened or to closed position, according as the operating motor is operated.

In the particular arrangement shown in 60 Fig. 1, compressed air is employed as the

motor operating medium. The supply of pressure medium to the motor, and to exhaust, being controlled by the magnet valves 13, 14, such supply being obtained from the reservoir 16, to which delivers a compressor 70 17. The parts so far described may be of the usual, or hand construction and arrangement now well understood in the art, and therefore requires no further description of the structure nor of the mode of operation thereof.

In a door operating installation, such as above described, it is also a common practice to employ a rock shaft 18 which is rocked by a magnet 19, which is commonly known as a door lock magnet, such rock shaft 18 having an arm 20 which is connected to be operated when the door lock magnet is energized so as to rock the shaft 18. An arm 21 also connected to shaft 18, 25 operates a lock stop 127, arranged to engage behind the rear edge of the door 10, when the latter is in closed position, to prevent the opening of the door. This lock device arrangement is also an expedient which is 30 frequently employed as a safety device in door operating systems of the nature referred to, the arrangement being such that when the door is closed the shaft 18 is rocked into position for the stop dog 127 to form 35 a lock to retain the door in its closed position, it being necessary to retract the stop dog before the door can be opened, such retraction being effected by the energization 40 of the magnet 19, manually, or otherwise as 45 may be convenient.

We will now describe the application of an emergency door opening mechanism embodying the principles of our invention, to a door operating system of the nature above referred to.

An auxiliary source of control current, such for instance, as a battery 23 or other source of current, independent of the usual and ordinary circuit arrangement employed in the door motor control system, is supplied, the circuit of which is controlled by a switch device indicated generally at A, see Fig. 8, and in accordance with our invention, we propose to provide manually operated means 11 to control the operation of switch device A, and we propose to so locate the manual control means for said switch device as to be readily accessible and available to anyone either within the car or outside of the car, 12 for effecting the operation of the switch device A. Various manually operated switch control devices may be employed for this purpose.

As illustrative of a practical arrangement, 13 we have shown a sliding weight 24 mounted within a casing 25, to slide vertically in guides formed in said casing. This casing with its sliding weight 24 is preferably located on the wall of the car near the upper 14

edge of such wall, and on the inside of the car. Weight 24 may be guided in its vertical movements by a guide rod 26 mounted upon the inner wall of the car. The weight 24 is connected by a cable or other flexible connection 27 arranged to operate over suitable guide sheave 28 to the switch device A for operating the lever. Instead of the connection 27 being directly connected to the switch device A, said connection is attached to the upper end of a rod 29, which is provided at its lower end with a hook member 30 disposed beneath the door operating lever 15 to engage the latter when the weight 24 is pulled downwardly so as to rock the door operating lever 15 and to thereby effect manually, when occasion requires, the operation of the door into open position.

In order to permit a like manual control and operation of the auxiliary switch device A, and of the door lever 15 from the outside of the car, a similar weight indicated at 31 is arranged within a casing 32 and guided by a guide rod 33, is disposed on the outer surface of the wall of the car near the upper edge thereof as clearly shown in Figs. 2 and 5. The weight 31 likewise is connected to the rod 29 through a cable or other connection 34 operating over suitable guide sheaves 35. The actuation of the switch device A by the movements imparted to rod 29 when either of the weights 24, 31 is pulled down from its normal or retracted position may be effected in various ways.

We have shown a simple arrangement wherein a lug or arm 36 is carried by the rod 29, and arranged when said rod is raised to engage the nose or end portion 37 of a pawl 38 pivotally mounted as at 39 in a bracket carried by the inner panel 40 of the wall so as to rock said pawl 38. Said pawl is provided with a projection or pin 41 arranged to extend through a curved slot 42 in the wall panel, and which pin or stud is engaged by a link 43 connected to a pivot arm 44 of the switch device A. A rod 45 connected to the rock arm 44 carries contact plates 46, 47, and 48. These contact plates respectively cooperate with pairs of circuit terminals 49, 50, and 51, for a purpose to be more fully explained hereinafter.

As above explained, the rod 29 is provided with a hook portion 30, to engage beneath the door operating arm or lever 15 when the rod 29 is moved upwardly by pulling down either of the weights 24, 31. The arrangement is such, however, that as the rod 29 is lifted, the dog 36 carried thereby engages and rocks the arm 38 from the position shown in Fig. 3 into the position shown in Fig. 7, before the hook end portion 30 of said rod 29 engages the lever 15, thereby effecting the operation of the switch device A. The result of this operation of the switch device A, as will presently be more

fully explained, is to close an auxiliary electric circuit through the door opening magnet 14, which controls the door opening movement of the motor 11, thereby effecting the power operation of the motor to open the door. In this event, of course, the hook portion 30 of rod 29 will not perform any function. If, however, the accident or other emergency which requires the operation of the switch device A, or the opening of the door, should result in rupture of the pressure supply to the motor 11, then, of course, the operation above described of the switch device A would be without result. In that event the hook portion 30 of rod 29 becomes effective to engage and lift or rock the door operating lever 15, thereby opening the door by manual power applied by pulling down one or the other of the weights 24, 31, thus affording a manually operated means for use in case of emergency, such as would render inoperative not only the electrical circuits employed in the normal control of the motor, but also the supply of pressure medium to the motor.

When the rock arm 38 has been shifted from its normal or retracted position as shown in Fig. 3 into its raised position shown in Fig. 7, by the engagement of the lug 36 therewith, thereby operating the auxiliary switch device A, any suitable means may be employed for retaining said arm in its raised position.

A simple arrangement for this purpose is shown wherein a spring 53 is connected at one end to the stud 41 at the upper end of link 43, and at the other end as at 54 to a suitable convenient fixed part 55 at a point such that the line of tension of said spring as the arm 38, is rocked by the pivot 39 of arm 38, as said arm is rocked into its raised position, thereby enabling said spring to retain the arm in its raised position.

In order to restore automatically the auxiliary switch device A to its normal position when the door lever 15 is again operated to close the door, and to permit said door operating lever to rock in door opening operation under normal conditions, without effecting the auxiliary switch A, we pivotally mount a dog 56 on the side of the door operating lever 15, said dog being provided with a lip or extension 57 which extends over the upper edge of said lever, a spring 59 serving to hold the dog 56 with the projection 57 resting against the upper edge of the door operating lever. The nose portion 60 of this dog is curved on its upper edge and is flat at its lower edge. This nose portion of the lever during the upward swing of the door operating lever 15 to open the door wipes by the stud 41 carried by pawl 38 without raising said pawl and hence without operating the switch A.

In the downward swing of the door op-

erating lever 15 in closing the door, the flat lower surface of nose 60 of dog 56, engages the stud 41, in case said stud has been raised in emergency operation of the apparatus as above explained, thereby depressing said stud 41, and overcoming the tension of spring 53 and causing the lever 38 to be forced downwardly and to snap into its retracted lower normal position.

- 10 In practice, and in order to prevent unnecessary or other tampering with the weight devices 24, 31, said weights are retained within the casings 25, 32 and facilitate the engagement of the weights by the fingers of an operator, to afford a grasp thereon for pulling the weights down in emergency operation, said weights are formed with openings indicated at 61. These cases are preferably protected by glass or other frangible plates 62, which in case of an emergency requiring emergency operation of the doors, may be readily broken, and for this purpose we provide a hammer device 63 with chain attachment 64, and which may be sustained in a suitable bracket 65 in convenient position on the wall of the car. In the case of the casing 31 on the outer side wall, a hook device 66, see Fig. 4, may be employed to engage the weight 31 within the casing to haul it down.

In practice, and in order to afford still further protection against derangement or unauthorized operation of the emergency apparatus, we prefer to lead the flexible connections 27, 34, intermediate weights 24, 31, and the lifting rod 29, through an enclosing pipe 67.

In order to return the rod 29 after being raised in emergency operation as the weights 24, 31 are restored into their casings 25, 32, we provide a spring 69 which is connected at its upper end to a lug 70 on the upper end of rod 29, and at its lower end as at 71, to a convenient fixed part or side wall panel.

45 Referring particularly to the diagram, Fig. 8, we have shown the circuit arrangement employed in the control of the motor in normal operation of the door, but since our present invention has to do with the 50 emergency operation of the door, description of the circuit arrangement for normal operation is unnecessary, and we will, therefore, confine our description of the operation to the operation of the emergency apparatus.

55 As above explained in the normal operation of the doors, switch device A occupies the position shown in Figs. 3 and 8. In this position the bridging contact members 46, 47 are out of bridging relation with respect to 60 circuit terminals 49, 50, while the bridging contact 48 is closed upon the terminal contacts 51. These contacts 51 are included in a circuit connection 72 in the circuit of the door lock magnet 19 and are used in the normal operation of the motor control system.

When, however, the weight 24 or 31 is pulled down, thereby actuating the switch device A, the bridging member 48 is displaced from bridging relation with respect to terminals 51 of circuit 72, thereby opening the circuit 73 of the door lock magnet and wholly disconnecting the emergency apparatus from the apparatus employed in the normal operation of the door motor control system. The same operation of switch A closes the bridging members 46, 47 upon their cooperating contacts 49, 50. The bridging of contacts 49 closes a circuit from the emergency battery or other current source 23, through conductor 73, across contacts 49, through conductor 72, and the door lock magnet 19. The energization of this magnet results in the rock arm 20 being actuated thereby rocking the shaft 18 and hence withdrawing the door stop or lock 127, this leaves the door free to be opened. The same movement of rock shaft 18, through the arm 74 closes a contact member 75 across terminals 76. These contacts are contained in series with conductors 77, 78. When, however, switch A is operated, a circuit is completed from emergency battery 23 through conductor 73, across contacts 50, through conductor 77, across contact 76, through conductor 78, and door opening magnet 14 to ground at 79, thereby causing the motor to be operated and the door to be opened. The closing of this circuit through the door opening magnet 14 would be without result, of course, in case the accident or other cause requiring emergency operation of the door should shut off the supply of operating medium to the motor. In that event, of course, the door will be opened as above explained manually by the hook portion 30 of rod 29 engaging beneath the door operating arm or lever 15.

From the foregoing description, it will be seen that we provide an exceedingly simple and efficient apparatus for the emergency opening of the door in case of accident, thereby increasing the safety of operation of street railway, subway, elevated and other cars or systems.

Many variations and changes in the details, construction and arrangement would readily occur to persons skilled in the art, without departure from the spirit and scope of our invention. We, therefore, do not desire to be limited or restricted to the exact details of the structure and arrangement shown.

Having now set forth the objects and nature of our invention, and a structure illustrative of the principles involved, what we claim as new and useful, and of our joint invention, and desire to secure by Letters Patent is:

1. In an emergency door operating apparatus, the combination with a door operating motor, and means to control the same in

normal operation, of auxiliary manually operated devices including a switch device said devices arranged to operate the normal motor controlling means independently of the 5 normal operation of said control means or to operate the door independent of the motor.

2. In an emergency door operating apparatus, the combination with a door operating motor, the control magnet therefor, and 10 means to control the circuit of said magnet in normal operation, of an auxiliary manually operated switch device to control said magnet independently of the normal control thereof, said auxiliary switch device being 15 normally in inoperative position, and means to automatically retain the same in operative position.

3. In an emergency door operating apparatus, the combination with a door operating 20 motor, the control magnet therefor, and means to control the circuit of said magnet in normal operation, of an auxiliary manually operated switch device to control said magnet independently of the normal control 25 thereof, said auxiliary switch being normally in inoperative position, means to actuate the same into operative position for emergency operation of the motor, and releasable means arranged to retain the same in its operative 30 position.

4. In an emergency door operating apparatus, the combination with a door operating motor, a magnet to control the same to open the door, and means to control the circuit of said magnet in normal operation, of 35 an auxiliary device independent of said door to control the circuit of said magnet independently of the normal control thereof, and manually actuated means to operate said 40 device.

5. In an emergency door operating apparatus, the combination with a door operating motor, a magnet to control the same to open the door, and means to control the circuit of 45 said magnet in normal operation, of an auxiliary device to control said magnet independently of the normal control thereof, and manually actuated means to operate said device, said manually actuated means also 50 arranged to open the door independently of said motor.

6. In an emergency door operating apparatus, the combination with a door operating motor, means actuated thereby to move 55 the door including a lever, a pivoted dog carried by said lever and means to control said motor in normal operation, of auxiliary manually operated devices to control said motor independently of the normal control 60 means to open the door, said dog operating when the door is again closed to restore said auxiliary device to normal condition.

7. In an emergency door operating apparatus, the combination with a door operating 65 motor, a door operating lever actuated there-

by and connected to the door to move the same to open and closed position, and means to control said motor in normal operation, and a switch device to control said motor in emergency operation independently of the 70 normal motor control means, a movable rod having a lug, means arranged to be engaged by said lug to actuate said switch device into operative position, means to retain said switch device in operative position, and 75 manually actuated means to move said rod.

8. In an emergency door operating apparatus, the combination with a door operating motor, a door operating lever actuated thereby and connected to the door to move the same to open and closed position, and means to control said motor in normal operation, and a switch device to control said motor in emergency operation independently 80 of the normal control means, a movable rod having a lug, a pivoted lever arranged to be engaged by said lug, said lever connected to said switch device to operate the same, and manually actuated device to shift said rod. 85

9. In an emergency door operating apparatus, the combination with a door operating motor, a door operating lever actuated thereby and connected to the door to move the same to open and closed position, and means to control said motor in normal operation, and a switch device to control said motor in emergency operation independently of the normal control means, a movable rod having a lug, a pivoted lever arranged to be engaged by said lug, said lever connected to 90 said switch device to operate the same, a spring connected to said lever to arrange to pass central relation with respect thereto when said lever is rocked into operating position, to retain said lever in its operated 95 position when manually actuating the device, for shifting said rod, and means to restore said lever and switch device to their normal position.

10. In an emergency door operating apparatus, the combination with a door operating motor, a door operating lever actuated thereby and connected to the door to move the same to open and closed position, and means to control said motor in normal operation, and a switch device to control said motor in emergency operation independently of the normal control means, a movable rod having a lug, a pivoted lever arranged to be engaged by said lug, said lever connected to 100 said switch device to operate the same, and manually actuated device to shift said rod, and means actuated by said rod to open the door independently of the motor. 105

11. In an emergency door operating apparatus, the combination with a door operating motor, a lever actuated thereby and connected to the door, and means to control said motor in normal operation, of an auxiliary switch device, a link connected thereto, a 110 115 120 125 130

- shiftable rod for actuating said link, a normally retained weight having connection with said rod for manual operation of the lever, said switch device operated to control 5 the motor independently of the normal control thereof to open the door, said rod having means to engage the motor to open the door independently of the motor.
12. In an emergency door operating apparatus, the combination with a door operating motor, a magnet to control the door opening movement of the motor, a normal circuit for said magnet for normal operation thereof, and an auxiliary circuit for said magnet, and 10 an independent current supply for said independent circuit, of an auxiliary switch for controlling said auxiliary circuit, and manually actuated device for operating said switch.
13. In an emergency door operating apparatus, the combination with a door operating motor, a lever actuated thereby and connected to the door, and means to control said motor in normal operation, of a shiftable rod having means to engage said lever to operate the same in door opening direction independently of the motor, and man- 15 ually actuated device connected to said rod to operate the same, and means also operated by the shifting of said rod to control the operation of the motor in door opening direction.
14. In an emergency door operating apparatus, the combination with a door operating motor, a lever actuated thereby and connected to the door, and means to control said motor in normal operation, of a shiftable rod having means to engage said lever to operate the same in door opening direction independently of the motor, and manually actuated device connected to said rod to operate the same, and means also operated by the shifting of said rod to control the operation of the motor in door opening direction, and a dog pivotally mounted on said lever arranged to restore said switch device to normal position when the door is again closed. 20
- In testimony whereof we have hereunto set our hands on this 9th day of August 50 A. D., 1923.

FRANK HEDLEY.
JAMES S. DOYLE.
